UNITED STATES PATENT OFFICE

WILLY HEIDINGER, OF BERLIN, GERMANY, ASSIGNOR TO THE TABULATING MACHINE COMPANY, OF ENDICOTT, NEW YORK, A CORPORATION OF NEW JERSEY

PUNCHING MACHINE

Application filed June 25, 1928, Serial No. 287,018, and in Germany March 16, 1928.

The invention relates to punching machines for perforating records and has for its principal object the provision of such a machine in which the operation of a single key or controlling member may result in selectively punching a record to indicate one of several meanings at the will of the operator.

A more specific object of the invention is to provide for punching record with numerical data in true or complementary form from the same keys or controlling members which may be marked with the true form of the data so that complements may be entered without mental calculation on the part of the operator.

The invention is particularly adapted to punching tabulator cards and is applicable either to single hole or multiple hole systems but for the sake of simplicity will be discussed in connection with a single hole system. A well known punching machine for perforating so-called single hole or Hollerith cards consists of a row of punches beneath which the columns of a record card are fed successively. The card is stopped with the several columns beneath the punches and the keys or controlling members are operated to effect operation of one punch for each column, the particular punch selected fixing the position of the perforation, which position in turn fixes the meaning of the perforation in the card. The Hollerith cards usually deal with numerical data and each column is divided into ten parts representing by their position the ten digits generally designated as "index point positions". A single operating member or key is provided for each punch and normally the operation of a key results in a punching operation by a selected punch. According to the present invention additional selecting mechanism is provided so that each key may select either its corresponding punch or another selected punch in the series. This is particularly useful in punching tabulating cards to be used in subtracting operations. It is common practice in automatic accounting machines to effect subtraction by adding positive items in their true values and negative items in their complementary values whereupon the accumulators or counters

show the balance between the positive and negative items. The complementary value of negative items necessary for subtraction in the decimal system is the true or tens complement of the items. In tabulating practice the tabulating cards may be punched with the tens complement of the figure in the units order of a number and the nine complements of figures in the other denominational orders or all figures of a number may be punched as nine complements and the additional unit necessary in the units denominational order entered through automatic operation of the tabulator. Both systems are in use and well known in automatic accounting machine practice.

In the present case a credit item is punched by the machine in its usual condition resulting in perforations corresponding to the operating key or members. A shifting mechanism is provided which disarranges the normal relationship between the keys and punches and substitutes another relationship in which each key selects the punch corresponding to its complementary value. In the usual subtracting operations the nine complements are used in which case the key or operating member designated 1 would selectively control the punch representing 1 or the punch representing 8, the other keys or operating members operating in like manner.

The invention is illustrated by way of example in the accompanying drawings in which,

Fig. 1 is a plan view of a well known form of key punch embodying the invention;

Fig. 2 is a longitudinal section of the punch shown in Fig. 1;

Fig. 3 is an enlarged detail of the punch mechanism in Fig. 2; and

Fig. 4 is a circuit diagram showing the punch selecting circuits.

The punch chosen for illustrating the invention is of well known form and fully described in the copending application of J. T. Schaaff, Serial No. 781,980, filed August 14, 1924 (Patent No. 1,821,078). A row of punches is indicated at 10, one for each index point position of a Hollerith card which may be controlled by controlling keys 11. The

punches are spring-pressed upward and guided at the lower end by guide plate 12 having a hole to accommodate each punch. Below the guide plate is a die plate 13 provided with a hole for accommodating each punch when it is depressed. Record cards 14 are fed one at a time by a suitable carriage between guide plate 12 and die plate 13 the movement of the carriage being governed by escapement mechanism which feeds each column of the card successively beneath the punches and after a punching operation feeds it automatically to the next column.

The operation of the punching mechanism 15 may be most clearly seen from Fig. 3. Each operating key 11 when depressed closes contacts 15 which are in circuit with a punch selecting magnet 16. Energization of this magnet attracts its armature rocking a lever 18 about its pivot and depressing a bar 19. The bar 19 is provided with a slot accommodating one arm of a bell crank 20 whose other arm is pivoted to an interposer bar 21. On energization of the magnet 16 to lower bar 19 the interposer bar 21 moves to the left in Fig. 3. Each interposer bar overlies a punch 10 and is provided with a notch 22 at its end which in normal position is directly beneath bail 23 but which when shifted by energization of its magnet moves to the left causing the bail 23 to coact with the higher surface of the interposer 21. The movement of any interposer 21 to the left rocks a bail 24 which in turn moves a hook rod 25 to the left thereby closing contacts indicated at 28. The closure of these contacts results in energization of punch magnet 29 which through suitable linkage 30 rocks bail 23 counterclockwise. Any interposer which is in normal retracted position will present its notch 22 to the bail so that movement of the latter does not result in movement of the interposer but if any interposer is moved to the left as shown in Fig. 3, this movement of the bail depresses it resulting in punching by its corresponding punch 10.

The circuit for the punch selecting magnets is shown in Fig. 4. Interposed between the key control contacts 15 and the selecting magnets 16 are a plurality of groups of contacts 31 all operating in unison. With the middle contacts of these groups in their left hand position, each set of key contacts is connected directly to its selecting magnet 16. That is, the 1 contacts 15 are connected to the 1 selecting magnet; the 2 contacts to the 2 selecting magnet, and so on. When the movable contact of group 31 is shifted to the right as shown in the drawings, each pair of key operated contacts 15 is connected to the punch selecting magnet 16 corresponding to the complement of the number represented by the keys, that is the 1 set of contacts 15 are connected to the number 8 selecting magnet, the

number 2 contacts are connected to the number 7 magnet, etc.

With the contacts 31 in this position then, operation of the keys will result in punching the nine complements on the cards. 70

While the exemplary disclosure is limited to thus transposing for complements it will be noted that numbers represented by the keys could be transposed for punching in other manners or that if desired, the selecting contacts could result in selective punching of single holes or combinations according contacts could result in selective punching-selecting magnets may also be selected by members other than the keys 11. The wires 32 in Fig. 4 are connected to the number keys of a typewriter so that these number keys may be operated instead of the punch keys 11 to select the different punches. 80

The method of shifting the contacts 31 85 is shown in Fig. 2. The machine is provided with a key 33 marked D (Fig. 1) and a key 34 marked C. Depression of the key 33 or debit key results in punching complements that is in shifting the contacts 31 to the position shown in Fig. 4 while the depression of the key 34 called the credit key results in shifting the contacts 31 to their alternative position to select true values for punching. 90

The operation of the debit and credit keys 33 and 34 is shown in Fig. 2. The bell crank 35 pivoted at 38 carries an insulating member 39 which coacts with the middle contacts of groups 31. With the bell crank in the position shown in Fig. 2 the right hand contacts 31 are closed and the left hand contacts are open which is the position for selecting true values for punching. When the debit key 33 is depressed bell crank 35 is rocked counterclockwise shifting the middle contacts 31 so that the left pairs close and the right pairs open. When the bell crank is rocked in this manner a pin 40 on key 34 engages a slot 41 in a member attached to bell crank 35 and latches the bell crank in its 105 counterclockwise position to hold right hand contacts 31 closed. In this position the complementary punches are selected for punching. The contacts may be shifted back to normal position by depressing the credit key 34 110 in which case the pin 40 is lowered out of the notch 41 and a spring 42 returns bell crank 35 to a position shown in the drawings again closing right hand contacts 31.

The invention has now been described in connection with a single illustrative embodiment but it will be understood that many modifications will readily occur to those skilled in the art and the invention is limited only as indicated by the scope of the following claims. 120

I claim:

1. A punching machine for perforating tabulating cards comprising a plurality of manually operated controlling members, 130

punching means comprising a corresponding number of punches for punching different data of a given group and connections between the controlling members and the 5
punching means to control the latter to punch data of the group individually appropriate to the several controlling members on operation of the same and means for selectively shifting the connections between the plurality 10
10 of controlling members and the corresponding punches to cause a controlling member to punch different data by the selection of either of a plurality of punches of the aforesaid given group on operation of the 15
controlling member.

2. A punching machine for perforating tabulating cards comprising a plurality of controlling members, punching means controlled thereby to perforate a record in different index point positions for each controlling member and a single device shiftable for operatively associating a plurality of said controlling members with the same said punching means in a plurality of different ways to selectively punch a record in one of several different index point positions on operation of each controlling member.

3. A punching machine for perforating records comprising a plurality of punches, a plurality of operating members for effecting operation of all of said punches, manually operated keys for controlling said members, and shiftable means for operatively associating said punches and operating members together selectively in different combinations to effect selection of either of a plurality of different punches by the key related to a particular individual operating member while maintaining all of said punches under control of the controlling members, regardless of the selective association.

4. A punching machine for perforating records comprising a plurality of punches, a plurality of controlling members equal in number to the punches, manually operated means for selecting said controlling members and shiftable means for selectively associating each controlling member with one of several punches whereby operation of each controlling member effects punching by any one of a plurality of punches.

5. A punching machine for perforating records comprising a plurality of punches with electrically operated selecting means for the same, a plurality of controlling members and a switch operated by each, and shiftable switching mechanism for selectively connecting all the switches and all the electrically operated selecting means together in different combinations whereby each controlling member may selectively control several different punches.

6. A punching machine for perforating records comprising a plurality of punches each having an electrically operated select-

ing device, a plurality of controlling members equal in number to the punches and a switch operated by each for controlling a selecting device and a gang switch with means for moving the same to a plurality of positions said gang switch including contacts for connecting a different switch with each selecting device for each position of the gang switch.

7. A punching machine for perforating records comprising a plurality of controlling members, punching means comprising a set of punches controlled thereby to perforate a record to manifest numerical data and a single device shiftable for selectively associating a plurality of controlling members with the punching means to effect at will punching from the same set of punches corresponding to either the true data represented by the controlling members or the complements thereof.

8. A punching machine for perforating records comprising a plurality of digit controlling members and a plurality of corresponding digit punches controlled thereby to perforate a record according to the operation of the controlling members and a single device shiftable for selectively associating the plurality controlling members with the punches to effect operation of either the digit punches corresponding to the controlling members or the digit punches complementary thereto on operation of the controlling members.

9. A punching machine for perforating records comprising a series of controlling members corresponding to the several digits, punching means comprising a set of punches controlled thereby to perforate a record to manifest numerical data and normally connected with the controlling members to effect punching corresponding to the true values represented by the controlling members and a single key controlled means for rearranging the connection between the series of controlling members and the punching means to effect punching corresponding to the complementary values represented by the controlling members by the same set of punches.

10. A punching machine for punching records comprising a plurality of digit controlling members arranged to normally represent an ascending order of digits, a plurality of corresponding digit punches controlled thereby, and a single manually operated means shiftable for selectively associating the plurality of digit controlling members with the digit punches in an order inverted with respect to their normal connection to represent a descending order of digits.

In testimony whereof I hereto affix my signature.

WILLY HEIDINGER.
